UNITED STATES PATENT OFFICE.

GEORGE S. EMERICK, OF PHILADELPHIA, PENNSYLVANIA.

AIR-SEPARATOR.

No. 826,772.

Specification of Letters Patent.

Patented July 24, 1906.

Application filed January 5, 1905. Renewed May 26, 1906. Serial No. 318,881.

To all whom it may concern:

Be it known that I, GEORGE S. EMERICK, a citizen of the United States, residing at No. 125 Osborne street, Wissahickon, in the city of Philadelphia and State of Pennsylvania, have invented a new and useful Improvement in Air-Separators, of which the following is a specification.

My invention relates to improvements in machinery whereby relatively fine material of any description may be separated into further grades of fineness by means of the weighing action of air-currents in combination with means for distributing said material to the action of such air-currents by centrifugal force.

To accomplish this object, my invention involves the features of construction and combination or arrangement of devices hereinafter described and claimed, reference being made to the accompanying drawing, in which the figure is a vertical section of the entire apparatus.

In the figure, A is an outer casing having the inner casing B concentrically disposed within and provided with the auxiliary chamber C. The rotatable hollow shaft D is mounted in the top of the casing A in the bearings E and actuated by the pulley F. Upon the hollow shaft D are mounted the fans G, and upon the lower end of said shaft is mounted the discharge-plate H. Within the hollow shaft D is located the non-rotary feed-pipe I, having mounted in its upper end the hopper J and supported by the frame K. To the inner periphery of the casing B is secured the cylindrical ring L, which I term a "retarding-ring," so disposed as to leave passage-way between its outer side and the inner periphery of the casing B and likewise a passage-way between its inner side and the lip of the discharge-plate H. The casing B is furnished at its lower end with the outlet M. The chamber C is secured to the lower end of the casing A and communicates with the casing B by means of the pipes N, furnished with suitable valves or dampers O and with the cover P, shown in the upper elbow of one of said pipes N.

The mode of operation of my improved air-separator is as follows: The material to be separated being introduced by the hopper J into the feed-pipe I is deposited upon the discharge-plate H, which, together with the fans G, is rotated by means of the hollow

shaft D and pulley F. The rotation of the discharge-plate H distributes the material deposited thereon by centrifugal action outwardly against the retarding-ring L. The rotation of the fans G creates a draft or upward current of air, which carries the fine particles of material thrown outward from the discharge-plate upward through the top of the casing B and into the casing A, through which said particles fall or settle to the bottom of said casing and passing through the chamber C are finally discharged at the outlet Q. The coarser particles of material distributed from the discharge-plate are not carried upward by the draft of air above described, but fall by gravity to the bottom of the chamber B and passing out through the outlet M may be collected for reintroduction into the hopper J or for further pulverization, as the case may be.

The two features wherein my invention consists are, first, the cylindrical retarding-ring L, whereby the material discharged from the plate H is prevented from passing to the inner wall of the chamber B, where the ascending air-current has little or no opportunity to pick it up. The office of the retarding-ring is to hold the material discharged more completely in the ascending current of air, and thus contribute to fuller and more ready separating action of such air-current. The second feature of my invention consists in the arrangement of pipes N, whereby instead of drawing the supply of air from without the apparatus I am enabled to use the same air in a continuous current, the circulation of air being shown by the arrows, as indicated in the drawing. The circulation of air in the pipes N can be controlled by the dampers O, and any tendency to a deposit of material carried in suspension by the air-current along the horizontal sections of the pipes N is provided for by the cover P, which consists of a removable section of the pipe N at a point where the accumulation of material in the horizontal sections of the pipes N at 100 can readily be reached and removed should such accumulation take place.

What I claim as my invention, and desire to secure by Letters Patent, is--

1. In combination, in an air-separator, an outer casing, an auxiliary chamber joined to and communicating with the outlet of said outer casing, an inner casing disposed within said outer casing, and a plurality of pipes

22 forming a connection between said auxiliary chamber and said inner casing, substantially as and for the purposes described.

2. In combination, in an air-separator, an outer casing, an auxiliary chamber joined to and communicating with the outlet of said outer casing, an inner casing disposed within said outer casing, means such as pipes N, forming a communication between said auxiliary chamber and said inner casing, a rotary discharge-plate adapted to centrifugally distribute material within said inner casing, and a cylindrical retarding-ring between said dis-

charge-plate and said casing, whereby the material distributed from said discharge-plate is checked in its passage toward the wall of said inner casing and retained in the path of the ascending air-currents therein, substantially as described. 15

In testimony whereof I have signed my name to this specification in the presence of two subscribing witnesses.

GEORGE S. EMERICK.
